UNITED STATES PATENT OFFICE.

ABRAM JACKSON GRISSOM, OF WHITE WRIGHT, TEXAS.

AUTOMATIC GRAIN-MEASURING MACHINE.

SPECIFICATION forming part of Letters Patent No. 380,718, dated April 10, 1888.

Application filed November 18, 1887. Serial No. 255,523. (No model.)

To all whom it may concern:

Be it known that I, ABRAM JACKSON GRISSOM, a citizen of the United States, residing at White Wright, in the county of Grayson and State of Texas, have invented a new and useful Improvement in Automatic Grain-Measuring Machines, of which the following is a specification.

My invention relates to an improvement in automatic grain-measuring machines; and it consists in the peculiar construction and combination of devices, that will be more fully set forth hereinafter, and particularly pointed out in the claims.

In the accompanying drawings, Figure 1 is partly an elevation and partly a vertical sectional view of one side of my improved grain-measuring machine. Fig. 2 is a similar view of the opposite side thereof, not in section. Fig. 3 is a vertical central longitudinal sectional view of the same. Fig. 4 is a vertical transverse sectional view. Fig. 5 is an elevation of the discharge end of the grain-measuring machine. Figs. 6, 7, 8, and 9 are detailed views of the registering device. Fig. 10 is a detail view of the inner side of the cross-bar L.

A represents a series of vertical corner posts or standards, which have their upper ends connected in pairs by longitudinal side boards, B. Fig. 3 is a vertical central longitudinal sectional view of the same. Fig. 4 is a vertical transverse sectional view. Fig. 5 is an elevation of the discharge end of the grain-measuring machine. Figs. 6, 7, 8, and 9 are detailed views of the registering device. Fig. 10 is a detail view of the inner side of the cross-bar L.

D D' represent a pair of vertical standards, which are secured to the outer sides of the boards B at a suitable distance from one end of the same, and the said standards D D' project above and below the said boards. The upper ends of the said standards are connected by a cross-bar, E.

F F' represent a pair of vertical standards, which are arranged parallel with the standards D D', respectively, and have their lower ends connected with the boards B. The upper ends of the said standards F F' are connected by a cross-bar, G, which is parallel with the bar E.

H represents a hopper, which is supported on the bars E and G between the centers of the same, and is provided with a discharge opening, in which is a hinged door or valve, I, that is adapted to open and close the said discharge-opening.

The standards D and F are connected at a suitable distance from their upper ends by a

bar, K, and the standards D' and F' are connected at a suitable distance from their upper ends by a bar, L.

55

M represents an inclined chute, which has its upper end secured to the depending ends of the standards D D' and its lower end secured between the opposing sides of one pair of the standards A. The discharge end of the chute M is controlled by a hinged gate, N.

O represents a revoluble measuring-head, which is composed of a series of boxes, T, having their inner sides connected to a common axis, R. The boxes T are so arranged that one side of each box projects much farther beyond the axis than the opposite side.

S represents a series of sectors, which are arranged on one end of the revoluble heads, are concentric with the axis thereof, and are secured to the ends of the boxes T, spaces P of suitable width being left between the ends of the sectors.

From the center of the revoluble measuring-head, at the ends of the same, project trunnions U V. The trunnion U is journaled in an opening in one of the boards B, and the trunnion V is journaled in the shorter end of a lever, W, which has its fulcrum on the opposite board B. On the long arm of the lever W is secured a weight, X, which weight is adjustable thereon and is provided with a setscrew, by means of which it may be secured to the latter at any desired adjustment. The sectors S on one end of the revoluble head are provided on their outer sides with eccentric recesses Y.

Z represents a lever, which is arranged on the inner side of the bar K and is pivoted on the bolt A'. The lower end of this lever is weighted, so that the lever is normally maintained in a vertical position.

B' represents a rock-shaft, which is journaled in suitable bearings on the under side of cross-bar G, is provided at its outer end with a downward-extending arm, C', and is provided at its inner end with a curved arm, E', which bears against the bottom of the valve I.

G' represents a rod, which connects the lower end of the arm C' to the upper end of the lever Z. The ends of the boxes T which are opposite the sectors are provided each with a stop, H', and a stop, I', in line with and beyond the outer end of the stop H', and on the

inner side of the bar L is a stop, K', and a stop, L'.

M' represents a gravity-latch, which is pivoted on the inner side of the bar L, is provided near its pivotal end with a depending shoulder or offset, N', and the free end of the said gravity-latch is adapted to bear normally on the upper side of the stop K'.

O' represents a lever, which is pivoted on the inner side of one of the boards B, has its long arm adapted to bear against the eccentric grooves of the sectors S, and has its short arm connected to a retractile spring, P', the function of which is to keep the lever normally in engagement with one of the sectors, as shown in Fig. 1.

R' represents a rod, which is attached to the lever O' at a suitable distance from the upper end thereof, and the inner end of said rod extends through an opening in a register-box, S', which is arranged in one corner of the same.

The construction of the registering apparatus is as follows:

T' represents a transverse shaft, which connects the centers of the sides of the box S', and on the said shaft is journaled a series of disks, U', V', and W', each of which is decagonal in shape. The said disks being all of the same size, the faces of each disk are numbered from 0 to 9 consecutively, and the said disks are each provided with ten transverse openings arranged on a circle concentric with the centers of the disks. On the outer side of the disk W', which indicates units, is secured a ratchet-wheel, X', which is provided with twenty teeth.

Y' represents a spring-actuated pin, which is arranged in transverse aligned openings made in the outer disk, W', and in the ratchet-wheel X'. The outer end of this pin is normally projected beyond the outer side of the ratchet-wheel and enters an annular groove, Z', which is made in one side of the box S'.

A' represents a spring-actuated pin, which is arranged in one of the openings in the disk V', and the inner end of which normally bears against the inner side of the disk W'.

B' represents a series of spring-detents, which bear against the peripheries of the disks and serve to prevent the same from turning idly on the shaft.

C' represents a spring-detent, which engages the ratchet-wheel X' and prevents the same and the disk W', to which it is connected, from rotating in a retrograde direction. In the upper side of the annular groove G' is a cam-block, D', which extends transversely across the said groove and has one side inclined or beveled, as shown.

On the front or discharge end of the frame of the machine is secured a longitudinally movable rod, E', which is in guides or staples F', that are arranged at a suitable distance above the upper edge of the door or gate N.

At the inner end of the rod E' is a curved arm, G', which is adapted to bear against the outer side of the door N, and at the inner end

of the said rod E' is an arm, H', which is adapted to be engaged by a keeper, I'.

K' represents a sack-holder, which comprises a yoke, L', made of a metal rod bent substantially in form of the letter U, and having its arm secured on the under side of the chute, at the discharge end thereof, by means of keepers M', which permit the yoke to be forced inward under the bottom of the chute or drawn outward under the discharge end thereof, as will be readily understood.

The operation of my invention is as follows: The weighted lever W normally raises the trunnion V of the revoluble measuring-head to the level of the trunnion U, so that the stop I' will ride over the stop L' and will bear against the inner end of the stop K', the weight is adjusted on the lever W to indicate the number of pounds in a half-bushel of the grain to be measured, and the grain is fed through the hopper into the box T which happens to be on the upper side of the revoluble head. While the machine is in this initial position

the weighted lever Z is in a vertical position, with its lower end engaged by one end of one of the sectors, and the rod C' connected to the said weighted lever holds the rock-shaft B' in such a position that the arm E' thereof supports the valve or door I in a vertical position, thereby permitting an unobstructed flow of the grain into the upper box of the revoluble head. The lever O' meanwhile is at the rear limit of its stroke, with its upper end bearing against the face of the eccentric groove on one of the sectors, and the operating-rod R', which is attached to the said lever and passes through an opening in the inner side of the registering box, has its inner end out of engagement with

the teeth of the ratchet-wheel X' of the register. As soon as enough grain has been discharged in the upper box of the revoluble head to make a half-bushel, the weight of the same counterbalances the weight X on the lever W,

and the trunnion V descends with one side of the revoluble head, so as to bring the stop I' below and out of engagement with the stop K', and the preponderating weight of the measured portion of the grain beyond the axis of the revoluble head causes the latter to instantly turn, as will be readily understood, and discharge the contents of the box T into the chute.

At the initial movement of the revoluble head the weighted lever Z is turned on its pivot by the sector which engages its lower end, and thereby the rock-shaft B' is turned so as to close the valve or door I in the discharge-opening of the hopper, and thereby prevent the grain from escaping while the revoluble head is turning. When the head has turned through one-third of a circle, the grain in the box has been discharged into the chute, so that the weighted lever W has again elevated the trunnion V.

As the next box T is brought to the top of the revoluble head, its stops H' and I' pass on opposite sides of the stop L', so as to clear the latter, and the stop I' strikes the rear side of the offset or shoulder N' of the latch M',

and thereby the latch M' is released, so that the stop I' is moved forward, thereby causing the stop H' to bear against the outer side of the door N, and thereby preventing the door from closing.

As the revoluble head turns through another one-third of a circle, the stop I' strikes the rear side of the offset or shoulder N' of the latch M', and thereby the latch M' is released, so that the stop I' is moved forward, thereby causing the stop H' to bear against the outer side of the door N, and thereby preventing the door from closing.

As the revoluble head turns through another one-third of a circle, the stop I' strikes the rear side of the offset or shoulder N' of the latch M', and thereby the latch M' is released, so that the stop I' is moved forward, thereby causing the stop H' to bear against the outer side of the door N, and thereby preventing the door from closing.

As the revoluble head turns through another one-third of a circle, the stop I' strikes the rear side of the offset or shoulder N' of the latch M', and thereby the latch M' is released, so that the stop I' is moved forward, thereby causing the stop H' to bear against the outer side of the door N, and thereby preventing the door from closing.

As the revoluble head turns through another one-third of a circle, the stop I' strikes the rear side of the offset or shoulder N' of the latch M', and thereby the latch M' is released, so that the stop I' is moved forward, thereby causing the stop H' to bear against the outer side of the door N, and thereby preventing the door from closing.

so as to raise the said latch and permit the stop I' to pass under the offset or shoulder N', and as soon as the said stop I' clears the said offset or shoulder N' the latch drops by its own gravity, so as to throw its offset or shoulder behind the stop I', and thereby prevent the revolute head from turning in the wrong direction. The weight on the lever W serving to keep the trunnion V elevated, the stop I' engages the rear end of the stop K', and the revolute head is thereby locked with its uppermost box arranged under the hopper. While the revolute head is making the partial rotation thus described, the weighted lever Z, being on the upper side of the engaging-sector, is maintained by the same in such a position as to keep the door or valve I closed; but when the revolute head reaches the limit of its partial rotation, with its uppermost box arranged under the hopper, the sector has passed beyond the lower end of the weight-lever Z, and the latter instantly drops into one of the spaces P and reassumes its initial position, thereby causing the rock-shaft B' to open the valve or door I and permit the grain to fall into the upper measuring-box.

While the revolute head is describing its partial rotation, the operating-lever O', which bears against the eccentric groove or cam on one of the sectors at its outer end, is gradually pressed rearward by the said cam or groove, so that the rod R' is caused to engage one of the teeth of the ratchet X' and move the same a distance of one tooth, thereby turning the disk W' the corresponding distance, and when the revolute head reaches its initial position, before described, at the end of its partial rotation the cam-groove on the sector which has been in engagement with the lever O' passes beyond the same, and the spring instantly causes the said lever to reassume its initial position and to bear against the inner end of the cam or groove in the next succeeding sector, thereby withdrawing the rod R' and arranging the same in position to engage the next succeeding ratchet-tooth. The stop H' slides against the lower side of the stop L', and thereby directs the stop I' against the shoulder or offset of the gravity-catch. From the foregoing description it will be understood that as each succeeding measuring-box discharges its half-bushel of grain into the chute the disk W' of the registering device will be moved through the one-twentieth part of a circle, while the disks V' and U' remain stationary. When twenty half-bushels or ten bushels of grain have been measured, the disk W' has been caused to make a complete revolution corresponding to ten units, which brings the pin Y', which has described a complete circle in the annular groove Z', into contact with the inclined side of the cam-block D'. At the next succeeding partial rotation of the measuring-head the disk W' will move the space corresponding to one unit, and the pin Y' thereof, as it passes over the cam-block D', will be forced inward by the lat-

ter and caused to engage one of the openings in the disk V', so as to move the latter, which indicates tens, through one space with the disk W', when the number of bushels measured will be indicated as being one unit and one ten, or, in other words, eleven. When a hundred bushels have been measured, the disk W' will have been rotated ten times and the disk V' will have been rotated once, and the pin Y' will register with the pin A² in the disk V', and at the next movement of the disk W' its pin Y' will be forced inward by the cam-block and caused to force the pin A² inward, so as to engage one of the openings in the disk U', and thereby the said latter disk, which represents hundreds, will be turned one space, and so on. When three disks are employed in the register, as hereinbefore described, the same will keep a correct register of the number of bushels measured by the machine up to one thousand. By increasing the number of disks the register may be adapted to indicate any desired number of bushels. When a sufficient quantity of the grain has been measured in the chute to fill a sack, the operator draws the sack-holder forward, stretches the mouth of the sack over the same, and moves the rock-shaft E² inward in the keepers F², so as to cause its arm H² to clear the keeper or detent I², when the shaft or rod E² may be turned upward, so as to cause its arm G² to release its pressure on the door or gate N, when the weight of the superincumbent mass of grain will force the said door open and the grain will be discharged into the sack, after which the door and the rock shaft or rod will drop to their initial positions, and the operator will only have to move the rod E² outward a slight distance to cause its arm H² to be again engaged by the detent or keeper I², which will serve to keep the gate or door closed while the sack is being removed and an empty one substituted and grain is being measured into the chute.

When the measuring-machine is used in connection with a thrashing-machine to measure the grain as it is thrashed, an endless elevator of suitable form will be employed to deliver the grain from the thrashing-machine into the hopper of the measuring-machine.

Having thus described my invention, I claim—

1. The combination, in a grain-measuring machine, of the revolute head having the boxes provided with the stops I', the counter-balance-lever supporting one end of the axis of the head, and the stop K', to successively engage each of the stops I', and thereby arrest the rotation of the revolute head, substantially as described.

2. The combination of the revolute head having the boxes or compartments T, provided with the stops I', the weighted lever supporting one end of the axis of the head, the stop K', adapted to engage each of the stops I' in succession, and the latch M', having the shoulder or offset N', adapted to be tripped by the

stops I' and fall behind the same, and thereby prevent retrograde rotation of the head, substantially as described.

3. The combination of the hopper having the valve I, the measuring-head having the boxes or compartments adapted to pass in succession under the hopper and provided with the cam-sectors having the spaces P between them, the lever Z, adapted to be engaged successively by the said cam-sectors and to drop into the said recesses, and connections between the said lever and the valve to automatically close the latter as each measuring box or compartment passes from under the hopper, substantially as described.

4. The combination of the revolute counterbalanced measuring-head having the boxes or compartments and the cam-sectors, the spring-actuated lever O', bearing against the said cam-sectors in succession, the registering mechanism, and connections between the same

and the lever O', whereby the latter will automatically operate the registering mechanism as the head revolves, substantially as described.

25

5. The combination of the revolute counterbalanced measuring-head having the boxes or compartments and the cam-sectors, the spring-actuated lever O', engaging the said sectors in succession, the registering mechanism having the operating ratchet-wheel, and the rod attached to the lever O' and adapted to engage and operate the ratchet-wheel as the head revolves, substantially as described.

In testimony that I claim the foregoing as my own I have hereto affixed my signature in presence of two witnesses.

ABRAM JACKSON GRISSOM.
